(57) **CLAIM**

The ornamental design for a trike as shown and described.

DESCRIPTION

FIG. 1 is a front view of a trike showing our new design;
FIG. 2 is a rear view thereof;
FIG. 3 is a left side view thereof;
FIG. 4 is a right side view thereof;
FIG. 5 is a top view thereof;
FIG. 6 is a left side view thereof in an alternate position;
FIG. 7 is a front view of another embodiment thereof;
FIG. 8 is a rear view thereof;
FIG. 9 is a left side view thereof;
FIG. 10 is a right side view thereof;
FIG. 11 is a top view thereof;
FIG. 12 is a left side view thereof in an alternate position;
FIG. 13 is a front view of another embodiment thereof;
FIG. 14 is a rear view thereof;
FIG. 15 is a left side view thereof;
FIG. 16 is a right side view thereof;
FIG. 17 is a top view thereof;
FIG. 18 is a left side view thereof in an alternate position;
FIG. 19 is a front view of another embodiment thereof;
FIG. 20 is a rear view thereof;
FIG. 21 is a left side view thereof;
FIG. 22 is a right side view thereof;
FIG. 23 is a top view thereof; and,
FIG. 24 is a left side view thereof in an alternate position.
The broken lines and portions within broken lines depict portions of the trike which form no part of the claimed design.

1 Claim, 24 Drawing Sheets
